ATTORNEY

Patented Nov. 17, 1925.

UNITED STATES PATENT OFFICE.

WILLIAM N. KNOWLTON, OF JACKSON HEIGHTS, NEW YORK.

JACK.

Application filed April 21, 1925. Serial No. 24,732.

To all whom it may concern:

Be it known that I, WILLIAM N. KNOWLTON, a citizen of the United States, residing in Jackson Heights, in the borough of 5 Queens, city of New York, county of Queens, State of New York, have invented certain new and useful Improvements in Jacks, of which the following is a specification.

This invention relates to built-in or self 10 contained jacks for motor vehicles, and my improvements are directed to certain novel and simple structures and arrangements of parts whereby the vehicle may be lifted and again lowered at points adjacent its respective 15 wheels to clear the latter individually from the surface, for tire changing and other purposes, by the simple expedient of applying a crank to a shaft.

My invention includes the provision of a 20 tubular device which is adapted to be secured to an axle of a motor vehicle, a jack element which is capable of vertical movement in said tubular device, but is non-retentable therein, said jack element having an 25 external thread, and a worm gear having an internal thread engaged with the thread of said jack element, said worm gear having a thrust bearing lying against the lower end of said tubular device, so that rotation of 30 said worm gear, in opposite directions has the effect either of extending the jack element or contracting it.

The worm gear is to be driven by a worm shaft which is journalled in a hanger that 35 may be carried by or form a part of the tubular device, this worm shaft having suitable driving connections whereby it can be actuated.

Preferably I provide means for driving 40 the worm shaft at different speeds, using a geared up drive for lowering the jack to the surface and raising it therefrom, these operations being performed without load, and therefore capable of quick performance. But 45 when the jack element has been lowered to the surface and it is desired to lift the motor vehicle the driving means is direct to thereby provide suitable driving power, thus enabling the motor vehicle to be conveniently 50 lifted by manual operation.

The worm shaft which thus actuates the jack element to raise and lower it and the vehicle is as stated journalled at one end in a hanger carried by an axle of the motor 55 vehicle. Since the axle is carried by the usual spring suspension means and the worm

shaft at its other end is journalled in a bearing having fixed relation to the chassis, I have found it necessary to provide means of compensation for the play that occurs as the 60 suspension springs flex and the tires yield when the vehicle travels over a rough surface. Otherwise the strains imposed upon the worm shaft would distort or break it. Therefore said worm shaft is rendered telescopic so that it may extend and contract in 65 length, and it is also provided with universal joints which permit it to yield in the manner of a flexible shaft.

Other features and advantages of my invention will hereinafter appear.

In the drawings:

Figure 1 is a side elevation of a motor vehicle equipped with my improved jack mechanism.

Fig. 2 is a section on the line 2—2 of Fig. 1.

Fig. 3 is a top plan view of the rear portion of the chassis, showing the differential and my improved jacks as applied to the 80 rear axle.

Fig. 4 is an enlarged section on the line 4—4 of Fig. 3.

Fig. 5 is a side view, partly in section of Fig. 4, showing the jack extended, and

Fig. 6 is a section on the line 6—6 of Fig. 5.

In said views I have shown my improved jacks as applied to the front and rear axles 1 and 2 of a motor vehicle, adjacent the 90 wheels at one side of the vehicle, and although both front wheels are not illustrated it will be understood that similar jacks are applied to serve the respective wheels.

Also in the detail views my improvements 95 are shown only as a single jack assemblage, because the respective jacks with their supporting and actuating means are all alike.

In the example illustrated the rear axle 2 is shown as provided with a sleeve 3, forming part of the differential housing 4. Henceforth in the description this sleeve 3 will be referred to as an axle, since for the purposes of my invention it has the same relation therein as the rigid front axle.

In any one of the jack assemblages let 5 indicate a tubular portion of a fitting or casting from which there extends a socket portion 6 adapted to receive an axle, a cap 7 completing the encirclement of said axle and 110 being secured to the socket portion 6 by screws 8. Also a set screw 9 is entered

through the cap portion to localize the fitting upon the axle.

The tubular portion 5 is fitted with a lining 10 that extends beyond said tubular portion at both ends, being provided at its lower end with a head 11 that abuts against the lower end 12 of said tubular portion, and having a collar 13 at its upper end that binds against the top of said tubular portion.

10 The jack element, as here represented, is of composite character, being composed of an externally threaded tube 14, slidably disposed within lining 10, and carrying an internally threaded worm gear 15, which is 15 in thrust bearing relation to lining 10, beneath the head 11 thereof, so that the tube 14 will be lowered or raised according to the direction of rotation given the worm gear 15. A casing 16, secured as by screws 20 17 to the tubular portion 5 of the fitting, serves to enclose the worm gear and receives the threaded end of a worm shaft 18 that is journalled in a hanger 18^a forming a part 25 of the fitting and being an extension of the tubular portion 5, said worm shaft meshing with said worm gear, to actuate it.

The externally threaded tube 14, forming part of the jack element, has closure means 19 at its lower end, with a terminal sphere 20, seated in a foot or base member 21, in which it is held by means of a cover plate 22, this ball and socket connection enabling the jack to accommodate itself to inequalities of the surface upon which it may be imposed. Slidably fitting within tube 14 is a squared rod 23. Pins or studs 24 extend inwardly from tube 14 to bear against opposite sides of this squared rod as an example of means for preventing relative rotation between the rod and tube. Said rod 23 projects at its upper end through a cap 25 which is secured as closure means upon a sheathlike extension 26 of tubular portion 5, that serves to house the upper end of tube 14 when the jack is not in use. Thus in effect the tubular portion 5 and sheath 26 constitute a housing for the jack element. The projected end of rod 23 receives a nut 27 that binds it to cap 25, thereby preventing rotation of said rod.

It will now be appreciated that when the worm gear is rotated suitably, the jack element being in its retracted position shown in Fig. 4, this rotation will have the effect of lowering the jack to the surface, and, thereafter, further rotation of said worm gear will cause the vehicle to be raised by taking the wheel which is served off the surface, (see Fig. 5).

60 The worm shaft is of composite character as will be described hereinafter, and is provided with a bevel gear 28 that meshes with a bevel gear 29, carried by a shaft 30, which is journalled in a bearing 31 forming part 65 of a hanger 32, said hanger having a carry-

ing plate 33 which is bolted to the under side of the running board 34 of the motor vehicle. A web 35 is extended from the hanger 32 and plate 33, in parallelism to shaft 30, and has near its free end an offset 70 bracket portion 36 provided with a socket 37 for the reception of the worm shaft, said bracket portion 36 also providing an end bearing for the shaft 30, near the bevel gear 29. Direct drive is had through the shaft 75 30, bevel gears 29 and 28, to operate the worm shaft 18, said shaft 30 having a squared end 38 for engagement by a hand crank 39, and by these means the load may be conveniently raised from and lowered to 80 the surface. But when the jack is to be lowered to or raised from the surface I prefer to employ high speed gearing, an example whereof will now be described: Also journalled in the hanger 31 and bracket portion 85 36 is a shaft 40, parallel to shaft 30, said shaft 40 being squared at its end 41 for engagement by a crank handle, and having a plate 42 secured to its opposite end. Bolted to said plate is a gear wheel 43, whose gear teeth are internal, and a pinion 44 which forms a rear extension of bevel gear 29 is in mesh engagement with said internal gear. The gear 43 being relatively much larger in diameter than the pinion provides greater speed when the drive is applied, upon turning shaft 40, from the gear 43, through pinion 44 and bevel gears 29 and 28, to the worm shaft. Therefore it is this shaft 40 which is actuated when the jack alone is to be operated. A casing 45, secured to the bracket 36, serves to enclose the gear 43, pinion 44 and gear 29.

It has already been stated that the worm shaft is of composite character and by this it is meant that said worm shaft or driving connection is composed of jointed members to be capable of flexure, and that said members are in distensible and contractible relation for the reasons set forth.

Heretofore the worm shaft has been designated by the reference numeral 18, but the part or member thus designated actually comprises the shaft length bearing the worm thread which is in mesh engagement with worm gear 15. Said shaft length 18 as here shown is fitted slidably with a sleeve 46, having lengthwise slots 47 to receive pins 48 carried by shaft length 18, so that no relative rotation can occur between said members. A link 49 connects the shaft length 18 with another shaft length 50 by means of universal joints 51, 52, said shaft length 50 being entered and secured within the socket 37 provided in bracket portion 36. From the foregoing description it will be seen that a composite worm shaft has been provided which is both variable in its length and capable of freely flexing, thus permitting said shaft,

as a connecting element, to adapt itself to all the relative motion occurring between the rigid chassis and the yieldingly mounted axle, while preserving in full effect the 5 drive characteristics of said worm shaft for the operation of the jack.

Variations within the spirit and scope of my invention are equally comprehended by the foregoing disclosure.

10 I claim:

1. The combination with a motor vehicle having a chassis and a body portion, and axles and wheels carried by said chassis, of means for elevating a wheel comprising a 15 tubular housing secured to an axle and arranged substantially perpendicular thereto, and closure means for the upper end of said housing, a lining within said tubular housing having a head that abuts against the 20 lower end thereof, means upon the upper end of said lining to engage the upper end of said housing, an externally threaded tube forming a jack element within said lining, a rod having telescopic, non-rotatable relation with said externally threaded tube, said 25 rod being in fixed relation to said closure means, a worm gear mounted on said externally threaded tube and bearing against the lower surface of said lining head, a shaft 30 hanger carried by said tubular housing, a worm shaft journalled in said shaft hanger and meshing with said worm gear, and means carried by said body portion for rotating said worm shaft whereby to lower 35 or raise said externally threaded tube.

2. The combination with a motor vehicle having an axle, of elevating means carried by said axle, said elevating means being vertically reciprocable and normally held in 40 spaced relation with the surface, drive means for moving said elevating means at relatively high speed to and from the surface, means for increasing the power of said drive means, when operating under load conditions, and respective manually operable 45 means to selectively actuate said high speed and power increase drive means.

3. The combination with a motor vehicle having an axle and a body, of elevating means carried by said axle, said elevating means being vertically reciprocable and normally held in spaced relation with the surface, drive means for moving said elevating means at relatively high speed to and from 50 the surface, means for increasing the power of said drive means when operating under load conditions, a hanger carried by said body and parallel, crank actuatable shafts journalled in said hanger to selectively operate said high speed and power increase drive means.

4. The combination with a motor vehicle having an axle, of elevating means carried by said axle, said elevating means being 55 vertically reciprocable and normally held in

spaced relation with the surface, direct drive means for moving said elevating means under load conditions, geared up means to increase the speed of said elevating means when moved to and from its normal position, and respective manually operable 70 means to selectively actuate said direct drive and speed increase drive means.

5. The combination with a motor vehicle having an axle and a body, of a jack element carried by said axle, direct drive means carried by said body for moving said jack element under load conditions, geared up means also carried by said body for increasing 80 the speed with which the jack element is operated under idling conditions, and respective manually operable means for operating said direct drive means and geared up 85 means.

6. The combination with a motor vehicle having an axle and a body, of a threaded jack element, a housing therefor carried by said axle, means to prevent rotation of said jack element, revoluble means engaging the thread of the jack element to lower and 90 raise the latter, direct drive means carried by said body for operating said revoluble means under load conditions and means also carried by said body for increasing the speed 95 of said drive means under idling conditions.

7. The combination with a motor vehicle having an axle and a body, of a threaded jack element, a housing therefor carried by said axle, means to prevent rotation of said jack element, revoluble means engaging the 100 thread of said jack element, to lower and raise the latter, direct driving means carried by said body for operating said revoluble means under load conditions, means also carried by said body for increasing 105 the speed of said driving means under idling conditions, and respective means for actuating said direct driving and speed increasing means.

8. The combination with a motor vehicle having an axle and a body, and means for elevating said vehicle comprising a jack element carried by said axle, of a worm gear to operate said jack element, a worm shaft meshing with said worm gear, a bevelled gear on said worm shaft, said bevelled gear carrying a pinion, a hanger carried by said body, a drive shaft journalled in said hanger and carrying a bevelled gear which is in 110 mesh with said first-named bevelled gear to operate said jack element under load conditions, a second drive shaft also journalled in said hanger and carrying an internally toothed gear with which said pinion engages 115 to operate said jack element under idling conditions, and respective means for actuating 120 said drive shafts.

9. The combination with a motor vehicle having a chassis, a spring supported axle and wheels carried thereby, and a body por- 130

tion, of elevating means carried by said axle, a worm gear for actuating said elevating means, a telescopic worm shaft for operating said worm gear, a bracket secured to said body portion, a shaft length journaled in said bracket, a link in universal joint relation at its ends respectively with said telescopic worm shaft and shaft length, and means carried by said bracket to co-act with said shaft length for the operation of said telescopic worm shaft.

Executed this 20th day of April, 1925.

WILLIAM N. KNOWLTON.
